FURNITURE CARRIER

Donald B. Docherty, Rte. 1, Reynolds, Ill. 61279, and
Paul L. Danner, Box 36, Illinois City, Ill. 61259

Term of patent 14 years

Filed May 14, 1971, Ser. No. 143,721

Int. Cl. D8—05

U.S. Cl. D8—71

FIG. 1

FIG. 2

FIG. 3

FIG. 4

FIG. 5

FIG. 1 is a front and side perspective view of a furniture carrier embodying our new design.

FIG. 2 is a rear and side perspective view of a furniture carrier embodying our new design.

FIG. 3 is a front elevation thereof.

FIG. 4 is a side elevation thereof, it being understood that both sides of the carrier are identical.

FIG. 5 is a top plan view.

We claim:

The ornamental design for a furniture carrier, substantially as shown and described.
